UNITED STATES PATENT OFFICE.

ROBERT A. BAUER, OF GRAND RAPIDS, MICHIGAN, ASSIGNOR OF ONE-HALF
TO ANTON C. BAUER, OF SAME PLACE.

V-JOINTER.

SPECIFICATION forming part of Letters Patent No. 319,173, dated June 2, 1885.

Application filed May 9, 1884. (No model.)

To all whom it may concern:

Be it known that I, ROBERT A. BAUER, a citizen of the United States, residing at the city of Grand Rapids, in the county of Kent and State of Michigan, have invented a new and useful V-Jointer, of which the following is a specification.

My invention relates to improvements in V-jointers in which the carriage has a reciprocating horizontal motion upon the carriage-bed, which bed oscillates on a bolt near its center, so that a V-shaped cut may be made on the stock supported by the carriage; and the objects of my invention are, first, to convey the motion from the shaft to the carriage by means of a universal joint; second, to oscillate the carriage-bed and carriage automatically, as well as to automatically stop the motion of the carriage when it reaches the required point in either direction, and, third, to adjust the carriage so as to bring the stock thereon to or from the cutting saws or shapers. I attain these objects by the mechanism illustrated in the accompanying drawings, in which—

Figure 1 is a plan view of my invention, showing the relative positions of the carriage, carriage-bed, and saws. Fig. 2 is a rear elevation of the same. Fig. 3 is a sectional view of the carriage-bed, carriage, and supporting-frame on line xx of Fig. 2, but with the bevel-gearing shafts and saw-pulleys in perspective, in order to illustrate more clearly the working mechanism. Fig. 4 is a bottom plan view of a portion of the carriage. Fig. 5 is a set-bar rigidly attached to the carriage, and Fig. 6 is an adjusting-rod connected to the carriage-bed used in connection with the bar shown by Fig. 5 in adjusting the carriage; and Figs. 7, 8, and 9 are detached views showing the carriage, its connecting and operating parts and supporting-plates, and their relation to each other.

Similar letters refer to similar parts throughout the several views.

e is the frame of the machine, which is of iron or any other suitable material.

1 is a horizontal shaft. 2 is a bevel-pinion rigidly attached to shaft 1, and 3 is a bevel-pinion rigidly attached to sleeve K. The pinions 2 and 3 engage with the bevel spur-wheel 4, as shown.

V is a band-pulley rigidly attached to the sleeve K, and pinion 3, sleeve K, and band-wheel V turn on the shaft 1.

U is an idle or loose pulley used to receive 55 the belt M, and to transfer it from pulley V to pulley T, and vice versa.

T is a pulley rigidly attached to shaft 1. The belt M runs continually in one direction, and when the band revolves T the spur-wheel 4 60 is revolved in one direction, and when the band M revolves pulley V the spur-wheel 4 is revolved in the opposite direction, and the carriage is thereby given its reciprocating motion. The spur-wheel 4 is rigidly attached to 65 the upright shaft G, which shaft is supported in two journal-boxes on bar H.

E and E' is a bevel-gearing conveying the motion from the perpendicular shaft G to the arbor of cog-wheel 9. The arbor of cog-wheel 70 9 is connected to the bevel-gearing E by a universal joint, 7, so that the cogs on cog-wheel 9 may always be in line with the cogs on rack-bar 11.

F and F' are belt-pulleys for running the 75 saws A A'.

14 is the carriage-bed, supported on the frame e. It is provided with a longitudinal groove extending its entire length, which forms a way for the travel of the carriage. The carriage-bed is attached to the frame by a bolt, d, on which it turns a short distance, so that it may be adjusted with the carriage to or from either saw.

B is an arm supporting the journal-box of 85 arbor J of bevel-wheel E.

I is a bar for shifting the belt M. It is supported at one end by arm 5 and at the other by the pin O in lever P.

L and L' are two lugs or lips on I, one on 90 either side of belt M. The lever P turns on a fulcrum near its center, and is attached at its upper end to lever Q, which lever also turns on a fulcrum near its center, as shown in Fig. 1, and is attached by means of a bolt or rivet 95 to the shifting-bar 17. The bar 15 is attached to the carriage-bed by means of two bolts, b and b', passing through longitudinal slots in shifting-bar 15, as shown in Fig. 1, so as to allow a horizontal longitudinal movement of 100 the shifting-bar 15. The bar 17 is attached to the carriage-bed by bolts c e, passing through

longitudinal slots in bar 17, so as to allow a longitudinal movement to the bar 17. The bars 15 and 17 are locked together by means of the latch or catch 16, so that they move together. The shifting-bar 15 is also attached to the carriage-bed at either end by short bars turning on bolts or pivots, which bars are shown by 21 and 22, these short bars giving the tilting or turning motion to the carriage-bed 10 and carriage. The bar 17 has two spring-catches, (shown in Fig. 1 by 19 and 20,) and the carriage has two downward projecting lips, (shown in Fig. 1 by 18 and 18'.) The position of the carriage in Fig. 1 shows lip 18' in contact with spring-catch 20.

The operation of this part of my invention is as follows: Let the carriage be placed in the position shown in Fig. 1, the belt M being on pulley V, and apply the power, and the pulley V 20 conveys the power through sleeve K, pinion 3, spur-wheel 4, shaft G, bevel-gearing E E', cog-wheel 9, to the rack-bar 11 and carriage 10, and the carriage is moved from the position shown in Fig. 1 toward the other end of the carriage-bed until the lip 18 comes in contact with spring-catch 19 on the bar 17, when the bar 15 is carried a short distance with the carriage, and by means of connecting-bar 22 the bed and carriage are tilted or turned toward 25 the saw A'. The motion of the bar 15 takes with it bar 17, and by means of the levers Q and P the shifting bar I moves the belt M onto the idle-pulley U when the carriage stops.

S' is a chain or cord attached to lug 6' on bar I, which cord passes around the pulley R', as shown in Fig. 2, and then at right angles and over pulley E'', as shown in Fig. 3, downward to the pedal f at the front of the machine, and cord or chain S, connected to 30 lug 6, passes around pulley R and downward to a pedal, f'. By pressing on pedal f the belt M is shifted from the idle-pulley U to pulley T, when the motion is conveyed through shaft 1 to bevel-pinion 2 and spur-wheel 4, giving 35 a reverse motion to the spur-wheel and through it to the carriage, causing it to travel back until lip 18' strikes against the spring-catch 20, as shown in Fig. 1, above described, when the carriage-bed and carriage shift and the 40 belt M is passed onto the idle-pulley U, and the carriage stops. If at any time the operator desires to move the carriage back without shifting, he raises spring-latch 16, which disconnects bars 15 and 17, when the carriage 45 is carried backward and forward in the same line. The spring-catches 19 and 20 are so constructed that they can be turned down beyond the reach of the lips 18 and 18', when the carriage will not be shifted in moving. 50 The carriage-bed has a doubletrack, as shown at 13 in Fig. 1, so that the carriage may be adjusted toward or from the saws by merely placing it on the one or the other track. Beneath the carriage, and attached to it, is the 55 plate 26. Two screws, 25 and 25', attach the plate to the carriage. Plate 26 has projections a a a a, and above the plate 26, and be-

tween such plate and the upper part of the carriage, is the adjusting-rod 27, having beveled projections, which rest upon the projections a a a a of plate 26. The weight of the back edge of the carriage rests on plate 26. At either end of rod 27 is an adjusting-nut, 70 23 and 24, by means of which the rod 27 may be moved longitudinally, thereby elevating or 75 depressing the side of the carriage farthest from saws A A'. The stock to be worked being placed on the carriage next to the saws, the raising or depressing of the opposite side adjusts the stock to and from the saws. 80

Having thus described my invention, what I claim to have invented, and desire to secure by Letters Patent, is—

1. In a V-jointer, a carriage-bed pivoted at its center to a suitable frame, and which oscillates intermittently first in one direction and then in the other, in combination with a carriage which travels back and forth on said carriage-bed, mechanism which reciprocates said carriage, and intermittently-operating 90 mechanism which oscillates said carriage-bed, which latter mechanism is automatically set in motion by the carriage when it reaches its limit of motion in either direction, substantially as set forth. 95

2. The combination of the pivoted carriage-bed, mechanism which turns said bed on its pivot, a carriage which travels back and forth on said bed, a rack secured to said carriage, a pinion mounted on the carriage-bed which engages with said rack, mechanism which operates said pinion, and a universal joint which connects the shaft of said pinion with its operating mechanism, substantially as set forth, whereby said pinion and rack may properly 105 mesh at whatever angle the bed may be turned. 100

3. The carriage provided with stops 18 18', mechanism which moves said carriage back and forth, and a bar, 17, provided with catches 19 20, with which the stops 18 18' respectively 110 engage, and thus move said bar alternately in opposite directions, in combination with a sliding bar, I, mechanism which connects the bar 17 with said bar I, whereby the movement of the bar 17 is communicated to the bar I, and 115 a shifting mechanism which connects said bar I with the mechanism which reciprocates the carriage, whereby the motion of the carriage in either direction is stopped, substantially as set forth. 120

4. The carriage provided with stops 18 18', mechanism which moves said carriage back and forth, a bar, 17, provided with catches 19 20, with which the stops 18 18' respectively 125 engage, a sliding bar, I, mechanism which connects the bar 17 with said bar I, and a shifting mechanism which connects said bar I with the mechanism which reciprocates the carriage, whereby the motion of the carriage in either direction is stopped, in combination with vertically-movable pedals f f', and mechanism connecting said pedals respectively to the opposite ends of the bar I, substantially as set forth, whereby, after the movement of the car- 130

- riage in one direction has been stopped, the depression of one of said pedals moves said bar 1 and sets the carriage-operating mechanism in motion in the opposite direction.
- 5 5. The combination of the pivoted carriage-bed, the sliding bar 17, mechanism for sliding said bar, the sliding bar 15, mechanism which locks said bars 15 and 17 together, and links 21 22, pivoted, respectively, to opposite ends 10 of the bar 15, and the carriage-bed, whereby the movement of the bar 15 turns the bed on its pivot, substantially as set forth.
6. In a V-jointer, the saws A A', in combination with the oscillating carriage-bed provided 15 with a single track, 14, extending longitudinally along one side thereof, and with a double track, 13, extending longitudinally along the other side thereof, and a reciprocating carriage which travels on said tracks 14 and 13, provided with 20 a longitudinal groove on its under side, which engages with either one of the tracks of the double tracks 13, substantially as set forth.
7. The oscillating carriage-bed, the carriage which rests and slides on said bed, and the saws A A', in combination with a spring plate, 25 26, attached to the bottom of said carriage and along one side thereof, studs *a a* formed on said plate, which rest and slide on the carriage-bed, said studs having beveled faces on their upper sides, an adjusting-rod, 27, held 30 between the studs *a a* and the under surface of the carriage, said rod having inclined portions *s s*, which are held in contact with the beveled faces of the studs *a a*, and mechanism for adjusting said rod, whereby one side of the carriage is raised or lowered, substantially as set forth. 35
